WHEELED VACUUM CLEANER CART

Clarence D. Reece, Duluth, Minn., assignor, by
mesne assignments, to H. F. Woodward, Min-
neapolis, Minn.

Application July 16, 1949, Serial No. 105,220

6 Claims. (Cl. 15—257)

1

This invention relates to a new and useful improvement in wheeled conveyances and more particularly to a cart for supporting vacuum cleaners and attachments therefor.

There are now on the market certain vacuum cleaners which are made to slide on the floor or to be carried by a handle. When slid on the floor the useable length of the hose is shortened as the cleaning attachment is usually carried waist high. This invention comprehends furnishing a peculiar form of cart for supporting the vacuum cleaner unit of the type above described which permits free use of the vacuum cleaner attachments and at the same time permits the use of both hands for manipulation thereof.

The invention comprises certain novel combination and arrangements of parts as will hereinafter be more fully set forth in the claims. In the accompanying drawing, there has been illustrated one complete example of an embodiment of the invention, but it is to be understood it is presented for illustrative purposes only and is not to be accorded any interpretation such as might have the effect of limiting what is claimed as the invention short of its true and comprehensive scope in the art.

Figure 1 is a perspective view of the improved vacuum cleaner cart;

Figure 2 is a view of a spreader bar to be used in connection with the cart;

Figure 3 is a top plan view of the vacuum cleaner cart base;

Figure 4 is a sectional view taken along lines 1—4 of Figure 3; and

Figure 5 is a view of a stair guide.

Referring to the drawings in detail, the vacuum cleaner cart generally indicated as at 10 comprises a handle member 12 substantially U-shaped in form with the upper part 14 curved or inclined outwardly from the base so that the cart can rest on the wheels 30 and the upper part of the handle 14. When the cart is in this position the cleaner supported by the cart will extend in a substantially horizontal position. The ends of the handle 12 pass through openings in one end of the stair guide members 26 and then the ends of the handle are removably secured in openings 16 and 18 in the base 34. The openings 16 and 18 are located in the base 34 adjacent the rear portion thereof.

The vacuum cleaner support and vacuum cleaner attachments member 22 is positioned on the handle 12 and the spreader or support bars 20 are positioned so as to hold the member 22

2

in the proper position. The spreader 20 consists of two parts which are normally urged apart by suitable means such as spring 44. The ends of the bar 20 fit into openings in the handle 12. On the member 22 is secured vacuum support band 24 and attachment pockets 26. There may be as many pockets as desired and some of the pockets may be placed on the back side of member 22. To make it comparatively easy to take the cart up and down steps there is provided stair guides 28. The guides are at one end mounted on lower spreader bar 20. The other end of the stair guides are mounted on the base and are operatively held in place by the lower ends of handle 12 passing into the base. The stair guides are in the form shown in Figure 5 and are spaced adjacent the wheels 30.

The supporting wheels 30 are mounted on a suitable axle 32 and the axle is mounted in and adjacent the rear end of the base 34. The wheels 30 are so formed that the means for securing the wheels on the axle are so positioned that they cannot strike furniture or other objects. This may be accomplished as shown in Figure 1 where the axle 32 does not extend outwardly as far as the outer edges of the rubber tires mounted on the wheels 30 and the wheels may be dished inwardly as is shown in Figure 1.

The base 34 is supported at the rear by wheels 30 and the front end is supported by means 44. The front support means may take various forms but spaced-apart legs work very satisfactorily. Part of the top surface is depressed and resilient pads 36 are secured in the depressed portions. The end of a tank or pot type vacuum cleaner rests on the pads 36. Between the sections carrying the pads 36 is a channel which has the forward part 38 lower than the rim of the base 34. The rear portion of the channel slopes at 42 toward the bottom of the channel. Located between the forward end and the rear portion of the channel is raised portion 40. The arrangement of the channel permits the electrical plug to be connected to the cleaner without moving the cleaner from the cart, and improves the flow of air to and from the vacuum cleaner. The channel feature is of extreme importance in the combination. The channel extends substantially across the base from front to back. When a vacuum cleaner is secured on the base the air going to and from the cleaner passes through the channel. A vacuum cleaner will not function properly without an ample supply of air so a cart for supporting a vacuum cleaner while the cleaner is being used must be so constructed

that the proper amount of air passes through the cleaner. The most satisfactory method is to provide a depressed portion in the support surface to form a closed bottom channel similar to that shown in the drawings. If this is not done an opening directly through the support surface is utilized, but if such an opening is used the necessary air for supplying the cleaner disturbs the dust on the floor. The channel formed in the support surface must be of sufficient width to receive the nose end of the vacuum cleaner and hold it out of contact with the bottom of the channel. The depressed portion of channel through which the necessary air supply for the vacuum cleaner passes is in a different plane than the major portion of the support surface.

From the foregoing, taken in connection with the drawings, it will be apparent that there has been provided a wheeled cart that may be manipulated with facility when storing a vacuum cleaner and attachments as well as supporting the attachments that are not being used while the cleaning is in progress.

This is an improvement over my co-pending application, Serial No. 23,049, filed April 24, 1948 now Patent No. 2,636,207.

What is claimed:

1. A vacuum cleaner cart comprising a base member with the rim of the top surface in a plane above the remainder of the top surface, a handle secured to and adjacent the rear portion of the base, pads secured to the base inside the rim, a channel in the base extending between the pads, and a raised member in the channel and spaced apart from the ends of the channel.

2. A device of the class described comprising a base having a rear and a front edge, an axle mounted adjacent the rear edge of the base, wheels mounted on the axle, means on the front edge for supporting the base in a substantial horizontal plane, a substantially U-shaped handle connected to the base and extending upwardly therefrom, removably attached bars attached to the handle, curved stair guides having one end secured to one of the said bars and the other end operatively mounted on the base, and a channel extending substantially across the base.

3. A vacuum cleaner cart including a wheeled support base, a portion of the base surface being depressed below the remainder of the base surface, and adapted to seat one end of a tank or pot-type vacuum cleaner, said depressed portion of the base surface having an air flow channel formed therein below the surface thereof and extending substantially across the base, whereby air supplied from a vacuum cleaner supported on the base passes through the channel, below the depressed base surface, said channel having upwardly sloping ends deflecting the air upwardly, a handle means extending upwardly from the base with one end inclined outwardly therefrom, and stair guide means mounted on the base by the handle means at one end, and attached to the handle means at the other end.

4. A vacuum cleaner cart, a support base hav-

ing the upper surface depressed along the mid-section to provide a seat for one end of a tank or pot-type vacuum cleaner which is positioned on end on the depressed surface, said support base having a channel formed in its upper surface below the depressed surface extending midway of the depressed surface and having a bottom sloping upwardly adjacent its mid-section to provide a raised portion therein, and having upwardly sloping ends, and a substantially U-shaped handle removably attached to the base and extending upwardly therefrom.

5. A vacuum cleaner cart adapted to support a tank type vacuum cleaner in a vertical position comprising a base having front and rear edges, an axle mounted on the base adjacent the rear edge, wheels mounted on the axle, means on the front edge of the base to support the base in a substantially horizontal plane, a substantially U-shaped handle connected to the base and extending therefrom, stair guides having ends operatively secured to the handle and the other ends operatively mounted on the base and held in place by the handle, said base having an upper surface formed to seat one end of a tank type vacuum cleaner, and a channel extending substantially across the base from front to rear and having the ends thereof sloped upwardly forming a closed bottom air channel.

6. A vacuum cleaner cart for supporting a vacuum cleaner on one end during cleaning use comprising a base having a front and back portion with the upper surface divided by a closed bottom air flow channel, the air flow channel having one end terminating in a plane lower than the upper surface of the base but in a plane above the bottom of the air flow channel, a pair of wheels mounted on the base adjacent to the back portion, support means on the base adjacent the front portion, substantially U-shaped handle means extending substantially perpendicular from the base, one end of the handle inclined outwardly from the base, and stair guide means held on the base by the handle means passing through an opening in the stair guide means and the other end of the stair guide means operatively attached to the handle.
